A. D. LIGHTNER.

ROPE CLAMP.

APPLICATION FILED DEC. 7, 1917.

1,343,177.

Patented June 8, 1920.

Inventor
Arthur D. Lightner

By Chester H. Braselton
Attorney

UNITED STATES PATENT OFFICE.

ARTHUR D. LIGHTNER, OF TOLEDO, OHIO, ASSIGNOR TO THE WILLYS-OVERLAND COMPANY, OF TOLEDO, OHIO, A CORPORATION OF OHIO.

ROPE-CLAMP.

1,343,177.

Specification of Letters Patent.

Patented June 8, 1920.

Application filed December 7, 1917. Serial No. 206,117.

To all whom it may concern:

Be it known that I, ARTHUR D. LIGHTNER, a citizen of the United States, residing at Toledo, in the county of Lucas and State of Ohio, have invented certain new and useful improvements in Rope-Clamps, of which I declare the following to be a full, clear, and exact description.

This invention relates to an improved rope clamp. In shipping motor vehicles, it is customary to fasten the wheels thereof to the floor of the railroad car by means of a piece of rope or fabric passed around the spokes and felly of the wheel, the ends of said rope or fabric being secured to the floor of the car.

The principal object of my invention is to provide an improved rope clamp for securing the ends of the rope to the floor of the car, this clamp being of such a nature as to prevent the rope pulling out of the clamp so as to insure the motor vehicle being firmly and securely fastened to the floor of the car.

A further object of my invention is to provide an improved rope clamp of the class described, which can be very quickly, cheaply and conveniently manufactured, and which is of such a nature that the rope can be very quickly and conveniently secured to the floor of the car by means of this clamp.

Further objects, and objects relating to economies of manufacture and details of construction will definitely appear from the detailed description to follow.

I accomplish the objects of my invention by the devices and means described in the following specification. My invention is clearly defined and pointed out in the appended claims.

A structure constituting a preferred embodiment of my invention is illustrated in the accompanying drawing, forming a part of this specification, in which:

Figure I is a view in side elevation, illustrating clamps, constructed in accordance with my invention, used for securing the wheel of a motor vehicle to the floor of a car.

Fig. II is a top plan view showing a clamp securing in place the end of a rope.

Fig. III is a detail, sectional view, taken on the line III—III of Fig. II, and

Fig. IV is a detail, perspective view of a rope clamp.

In the drawings, similar reference numerals refer to similar parts throughout the several views, and the sectional view is taken looking in the direction of the little arrows at the ends of the section line.

Considering the numbered parts of the drawing, I have shown a rope clamp comprising the base flanges 10, and the U-shaped central portion 11, which is struck up from the base flange 10. Openings 12 are provided through the base flanges by means of which the clamp may be nailed to the floor. Openings 13 are provided through the top of the U-shaped central portion 11, and a groove 14 is struck downwardly, transversely of the central portion 11, as clearly shown in the drawing.

I have indicated the floor of a railroad car, or other relatively fixed part, by the reference numeral 15. The wheel of a motor vehicle is indicated at 16 and the spokes at 17. The wheel is secured in place by passing the rope 18 around the spoke 17, and securing the ends of the rope to the floor 15 by means of the improved rope clamp, which I have described. The clamp is secured to the floor 15 by means of nails 19, which are driven through the openings 12 in the base flanges 10 of the clamp. The rope 18 lies in the U-shaped central portion 11 of the clamp and the downwardly-struck groove 14, which forms a rib on the inner side of the U-shaped portion 11, pinches into the rope, as clearly shown in Fig. III. Nails 20 are driven through the openings 13 and the rope 18 into the floor 15.

It will be seen that, by means of this clamp, I have provided an improved device for securing the ends of a rope. The projecting rib 14, where it projects on the under side of the curved central portion 11, bites into the rope 18, so as to prevent its being pulled laterally of the clamp, and the nails 20, which pass through the openings 13 and the rope 18, also serve to prevent the rope being pulled out. The clamp is very conveniently secured to the floor 15 by the nails 19.

Having thus described my invention, what I claim as new and desire to secure by Letters Patent, is:

1. A securing device comprising a U-shaped central portion provided with a transverse groove formed therein, and base flanges extending in opposite directions from

the U-shaped portion and adapted to be attached to a plane surface whereby the U-shaped portion may serve as a securing means for a flexible member.

- 5 2. A securing device comprising a U-shaped central portion provided with a depressed portion formed therein and adapted to secure a flexible member to a plane surface, securing devices adapted to be passed 10 through the U-shaped central portion and the flexible member, base flanges extending in opposite directions from the U-shaped portion, and means for securing the base flanges to a plane surface whereby the flexible 15 member is engaged by the U-shaped

portion and retained against movement relative to the plane surface.

3. A rope securing device comprising in combination, a pair of base flanges, and a bridge portion connecting said flanges and 20 adapted to bridge the rope to be secured, said bridge portion having an inwardly projecting portion adapted to grip said rope, the height of said bridge portion being substantially equal to the thickness of the rope to 25 be secured whereby said base flanges and said rope may rest upon a plane surface.

In testimony whereof I affix my signature.

ARTHUR D. LIGHTNER.
